UNITED STATES PATENT OFFICE.

MORTON MAIER, OF NEW YORK, N. Y.

DENTAL CASTING-MACHINE.

1,110,954.

Specification of Letters Patent. Patented Sept. 15, 1914.

Application filed November 7, 1913. Serial No. 799,691.

To all whom it may concern:

Be it known that I, MORTON MAIER, a citizen of the United States, and a resident of New York, borough of Manhattan, in the county and State of New York, have invented a new and Improved Dental Casting-Machine, of which the following is a full, clear, and exact description.

My invention relates to dental casting machines, and has reference more particularly to the centrifugal type in which the molten material is forced into the mold by centrifugal force.

The object thereof is to provide a simple, inexpensive and convenient device whereby a perfect casting can be obtained.

I obtain the above object by providing a bucket adapted to receive a mold carrier and normally suspended in a vertical plane from a substantially horizontal arm provided with means whereby it can be rotated in a substantially horizontal plane, the centrifugal force generated by rotation tending to force the bucket from its normal vertical plane to a horizontal plane and whereby the molten metal in the mold carrier is forced into the shape of the mold.

The invention consists of the construction and combination of parts to be more fully described hereinafter and fully set forth in the claim:

Reference is to be had to the accompanying drawings forming a part of this specification, in which like characters indicate corresponding parts in all the views and in which:

Figure 1 is a vertical, longitudinal section of an embodiment of my invention; and Fig. 2 is a section on line 2—2, Fig. 1.

Referring to the drawings, 3 represents a bucket of any suitable material provided interiorly with reinforcing ribs 4, forming spacers therein for a mold carrier 5, preferably formed of a piece of tube, to receive therein the material 6 forming the mold proper. Two of the opposite ribs 4 are extended laterally, as shown at 7, with their extremities turned into a plane parallel to the axis of the bucket. Pivotal secured by any suitable means to the extremities of the extensions 7 is a bail 8, which is preferably provided with a rigidly secured central head 9 having a link 10.

An arm 11 having a snap hook 12 at one end, which is adapted to receive the link 10 of the bail, has its opposite end rigidly se-

cured to a substantially vertical shaft 13. The said shaft 13 bears in an extension 14 of a casing 15. The portion of the shaft 13 within the casing 15 is provided with a pinion 16 secured rigidly on said shaft and meshing with a gear 17 also positioned in the casing 15 and carried by a shaft 18 bearing in the cover 19 of the casing 15 and projecting through said cover. The projecting end of the shaft 18 is engaged by a crank 20 whereby said shaft can be rotated and therewith shaft 18, gear 17 secured to said shaft, pinion 16 meshing with said gear, shaft 13 rigid with the pinion and the arm 11 carried by said shaft 13, and therewith the bucket 3. The casing 15 is preferably mounted on a bar 21, whereby the said casing can be secured to any suitable place. Said bar 21 also forms a journal for the lower end of the shaft 18, so as to form a better support for the gear 17. A counterweight 24 is secured to the shaft 13 whereby the revolving parts are balanced. The arm 11, as shown in Fig. 1, is bent slightly downward so as to permit the bail 8 to pass freely under the bar 21 when the mechanism is rotating and the centrifugal force has reached the point where it forces the bucket with the bail into a substantially horizontal plane. The position of the bucket 3 with reference to the arm 11 is normally at right angles to that shown in Fig. 1. The displacement from the normal was made for the purpose of better illustration of the structure. That is to say, the substantially horizontal axis on which the bucket swings on bail 8 is at all times substantially perpendicular to the direction of the arm 11.

The reason for this is to permit the bucket which supports the mold carrier to remain in a substantially vertical position independent of the bail. That is, the bucket has a tendency to remain in a substantially vertical position not only on the snap hook 12 but also on the axis of its suspension on the bail. This provision reduces the possibility of splashing molten metal out of the funnel portion 22 formed in the material 6 of the mold proper wherein the molten material is poured before the device is set in rotation. And, as it can be seen, as long as the device does not acquire its maximum speed, the bucket will remain substantially vertical, or will be inclined very little, and with the increase in speed the said bucket will be moved to a horizontal plane, or sub-

stantially so, and the metal in the funnel will be forced by the centrifugal force into the mold 23.

Having thus described my invention, I claim as new and desire to secure by Letters Patent:

In a dental casting machine, a bucket having longitudinal reinforcing rods therein forming spacers for a mold carrier; a mold carrier therein; lateral extensions from said bucket; a bail pivotally secured to said lateral extensions whereby said bucket is adapted to swing in said bail on a substantially horizontal axis; a substantially vertical shaft; means for rotating said shaft; a sub-

stantially horizontal arm secured to said shaft; and means at the free end of said arm adapted to secure said bail but leaving to it the freedom to swing on said arm, said bail being so positioned on said arm that the swinging axis of said bucket is substantially perpendicular to the axis of said shaft.

In testimony whereof I have signed my name to this specification in the presence of two subscribing witnesses.

MORTON MAIER.
